UNITED STATES PATENT OFFICE.

ROBERT SCHLUMBERGER, OF ALLEGHENY, PENNSYLVANIA, ASSIGNOR TO
ALVIN S. KING, OF SEWICKLEY, PENNSYLVANIA.

AUTOMATIC WATER-HEATER.

SPECIFICATION forming part of Letters Patent No. 629,175, dated July 18, 1899.

Application filed January 17, 1898. Serial No. 666,892. (No model.)

To all whom it may concern:

Be it known that I, ROBERT SCHLUMBERGER, a citizen of the United States of America, residing at Allegheny, in the county of Allegheny and State of Pennsylvania, have invented certain new and useful Improvements in Automatic Water-Heaters, of which the following is a specification, reference being had therein to the accompanying drawings.

10 This invention relates to certain new and useful improvements in automatic water-heaters, and has for its object to provide novel and effective means whereby the water may be almost instantly heated.

15 The invention further aims to provide a water-heater which will be operated entirely by its own pressure and which is not controlled by the opening and closing of the cold-water supply.

20 The principal features of my invention reside in the automatic valve, which is operated entirely by the pressure of the hot water and which may be regulated to open and close the supply of gas when the pressure of the water 25 has reached a predetermined point.

The invention also includes a novel form of 30 burner and also a peculiar arrangement and construction of the coils, both of which have been made the subjects of separate applications, and which have therefore not been included in detail in these drawings and specification.

In describing the invention in detail reference is had to the accompanying drawings, 35 forming a part of this specification, and wherein like letters of reference indicate similar parts throughout the several views, in which—

Figure 1 is a perspective view of my improved water-heater as it appears when in 40 use. Fig. 2 is a vertical sectional view of the valve. Fig. 3 is a perspective view of the plunger within the valve. Fig. 4 is a like view of the supporting-stem for the plunger. Fig. 5 is a side view of a portion of the casing 45 of the valve, showing a slot arranged therein to admit the atmosphere within the case and prevent counter-pressure on the bottom of the plunger. Fig. 6 is a longitudinal sectional view of a portion of the boiler-casing and of the 50 burner. Fig. 7 is a perspective view of my improved water-heater, partly broken away at its side, showing the interlocking water-coil.

In water-heaters designed for instantaneous

heating as heretofore constructed the boiler has always been arranged in a vertical position, and it has been found difficult to feed the gas in a manner that the same would cover any great degree of surface of the coils. In my invention the heater is arranged horizontally and the pipes in which the water is heated are wound in coils that are interlocked with each other in a manner whereby the greatest possible amount of the coiling is obtained within the heater-casing. The gas is fed through my improved burner into contact with the coils and courses almost or entirely through the series of coils, so as to apply a direct heat to the water in all sections of the coiling.

In the drawings illustrated herewith the boiler or casing *a* is, as above stated, arranged horizontally and supported by a suitable stand *b*, although these may be of various other forms of construction than that illustrated herewith.

To the water-coils which are arranged within the casing *a* is connected the cold-water supply *c*, which is provided intermediate of its controlling-cock *d* and the casing with a check-valve *e*, which prevents any of the water passing through the coils back into the cold-water supply. To the opposite end of the coils or at any point where it may be desired is connected the hot-water supply, *f*, controlled at a sink or basin by an ordinary 75 cock or spigot *g*.

The gas-supply *h* is provided with a controlling-cock *k* and is connected with the screw-threaded end *l* of the valve-casing *m*, the gas-supply being also connected to the screw-thread *l'* on the opposite side of the valve and carried in any suitable manner forward, where it is connected at *l''* to the burner. The arrangement and connection of this gas-supply, as herein shown, have in practice been 95 found very satisfactory, although it will of course be observed that this connection may be made in any desirable way. This valve-casing *m*, it will therefore be observed, is supported by a gas-supply pipe and is provided 100 in its top with a screw-threaded opening, in which is secured a plug *n*, having a central opening to receive the plunger and supporting-stem *o*, which extends upward into the casing *p*, that is secured on and carried by 105 the plug or nipple *n*. Arranged within the

casing p , between the bottom of the same and the plunger q , and surrounding the plunger and supporting-stem o is a stiff tension-spring r , which serves to normally support the plunger and relieve its weight from the supporting-stem o , as will be hereinafter more fully described. Said plunger is preferably provided on its upper end with a gasket q' , which may be bound firmly to the top of the plunger by means of the plate q^2 , fastened in position by a screw q^3 engaging into the screw-threaded aperture q^4 , provided in the top of the plunger. Screw-tapped in the upper end of the casing p is a nipple s , to which the neck t is connected, the other end thereof being attached to the upright u , which is connected by the union V to the hot-water supply f at any suitable point thereon. The gas-valve casing m is provided with an ordinary transverse wall m' , in which is formed the valve-seat m^2 . The valve m^4 is carried by the stem m^5 and is held normally open by means of a tension-spring n' , which engages the head n^2 , provided on the lower end of the stem, said tension-spring being retained within its casing by means of the cap n^3 . Counter-pressure on the bottom of the plunger q is obviated by providing a slot n^4 in the side of the casing p , thereby preventing any compression of the air within the casing as the plunger is forced downward through the pressure of the heater.

The casing a is provided entirely around its periphery with one or more rows of apertures a' for the admission of the proper quantity of air to the gas, these apertures being preferably made at a point in close proximity to the series of gas-tips which are arranged on the burner.

My improved form of burner, of which a sectional view is given in Fig. 6, is fully described in detail in a separate application for Letters Patent and is for this reason described but briefly in this application. It comprises a drum a^2 , to which, as heretofore stated, the gas-supply pipe is connected at b^2 , this shell having a suitable door a^3 for lighting the gas, and on its inner face a^4 , and which abuts against the edge of the casing a , is provided a series of gas-tips a^5 . This shell is provided with lugs b^1 , arranged around its periphery and through which pass fastening-rods b^2 , extending the length of the casing and engaging in lugs b^3 , provided on the head b^4 , which incloses the other end of the casing and with which the flue b^5 communicates. The shell a^2 is provided with a suitable aperture c' for the reception of a pipe c^2 for the feeding of the pilot-light, the latter being composed of one of the gas-tips which are secured in the plate a^4 of the burner. Assuming, now, that the parts have been secured in their respective positions, the connections from the water-supply to the coil-pipe having been made and the gas for the pilot-light having been ignited, the controlling-cock d of the cold-water supply being opened the water passes

through the check-valve e until the coils of pipe within the casing have been filled with water, the check-valve preventing the water from passing backward into the cold-water supply. The hot-water spigot g may then be opened, and as the pressure of water from the heater reaches the predetermined point, which is regulated by the tension-spring n' , the water passing through the connections u and t and into engagement with the plunger q compresses the same and causes the plunger and supporting-stem o , which is in engagement with the valve m^4 , to force this valve firmly into its seat m^2 , and thereby check the supply of gas. As soon, however, as a sufficient quantity of the heated water has been drawn from the coils to lower the pressure of the same in the heater or the pressure is lowered by the cooling of the water the springs r and n' raise their respective plungers and valves by reason of the pressure on the top of the plunger having been relieved, thus permitting the gas to again flow through the casing m to the burner, where it is ignited by the pilot-light and burns until the pressure of the heater has again been raised to a point sufficient to repeat the heretofore-described operation. I desire to call particular attention to the fact that in this form of heater the supply of gas is controlled entirely by the pressure of the heater instead of being controlled by the opening and closing of the cold-water supply, as in the ordinary manner. As the pressure of the heater is being exerted upon the plunger, thereby causing the same to seat the valve and shut off the supply of gas to the burner, the counter-pressure on this plunger is relieved by providing a casing surrounding the same and having a suitable slot n^4 , by means of which the air admitted within the casing, and which would otherwise be compressed, is permitted to escape therefrom.

Having fully described my invention, what I desire to claim as new and secure by Letters Patent is—

In an automatic water-heater, the combination of a water-heating receptacle having a suitable supply and delivery connections, a gas-burner adapted to heat said receptacle and having a suitable supply-pipe, a valve in the gas-supply pipe, a spring for holding said valve normally opened, a piston-casing in proximity to the gas-valve, said casing being in communication with the delivery connection of the water-receptacle, a piston in said casing and connections between the said piston and gas-valve, the arrangement of parts being such that the piston is operated by the pressure of the water in the receptacle to seat the valve, substantially as set forth.

In testimony whereof I affix my signature in the presence of two witnesses.

ROBERT SCHLUMBERGER.
